W. L. CHILDS

BACKOUT DEVICE FOR DRILLING RIGS

Filed Sept. 10, 1921

Fig. 1.

Fig. 2.

W. L. Childs INVENTOR.

BY Jesse R. Stone

ATTORNEY.

UNITED STATES PATENT OFFICE.

WILLIAM L. CHILDS, OF HOUSTON, TEXAS, ASSIGNOR TO HUGHES TOOL COMPANY, OF HOUSTON, TEXAS, A CORPORATION OF TEXAS.

BACKOUT DEVICE FOR DRILLING RIGS.

Application filed September 10, 1921. Serial No. 499,643.

To all whom it may concern:

Be it known that I, WILLIAM L. CHILDS, a citizen of the United States, residing at Houston, Harris County, Texas, have invented a certain new and useful Improvement in Backout Devices for Drilling Rigs, of which the following is a full, clear, and exact description, such as will enable others skilled in the art to which it appertains to make and use the same.

My invention relates to a backout device to be used on rotaries in well drilling. The device is to be employed in combination with pipe tongs in unscrewing joints of pipe.

15 In removing a string of pipe from the well during the operation of well drilling, it is customary to unscrew the joints of pipe by use of the rotary and, as the joints are being uncoupled, to hold one portion of the 20 joint to be uncoupled with a pair of break-out tongs and to secure said tongs against movement by contact of the handle thereof with a breakout pin on the derrick platform. The other portion of the joint is gripped by 25 means of a second or backout wrench. This wrench is rotated about the pipe by contact with a breakout pin secured in an erect position on the rotary table. The pin contacts with the handle of the wrench and the rotation of the table swings the wrench and the pipe in the proper direction to unscrew the 30 threads at the joint. It has been found in ordinary practice that when the backout wrench has been thus gripped firmly upon the pipe, and the breakout pin is held rigidly against the handle of the wrench, the wrench cannot easily be released from this 35 locked position. It is usually necessary to jar the wrench loose by means of hammers.

40 It is an object of my invention to provide a backout pin which will serve to adjustably support the wrench in proper position and also to provide means for releasing the handle of the wrench when the joint has been 45 unscrewed.

50 Another object is to provide a backout pin, of the character described, which will be capable of vertical adjustment so as to grip the wrench supported thereon to the pipe at various heights above the rotary, and at the same time be capable of releasing the wrench in the manner described.

These and other objects and advantages

will be more fully set forth in the specification which follows.

Referring to the drawing herewith where-in the preferred embodiment of my invention has been shown, Fig. 1 is a top plan view of a rotary table and pipe showing my improvement employed in connection with the handle of a wrench, said pipe being in transverse section. Fig. 2 is a side elevation of the device. Like numerals of reference are employed in both views in designating like parts.

In the drawing I have shown, more or less diagrammatically, an ordinary type of rotary table used in connection with the rotary system of drilling. This table 3 is mounted upon a lower base 4 supported upon the beams 5. The table 3 is provided at its outer, lower edge with gear teeth which are adapted to mesh with a bevel gear 6 on the power shaft 7. By this means the table 3 is rotated upon the base 4. Centrally of the table is a circular opening through which the pipe 8 may project. On either side of this opening in the rotary table I may provide openings 9 in which may be removably received my improved backout 80 post 10. At one side of the rotary table and connected with the rotary base or with the derrick platform, I may provide an up-standing breakout pin 11 of any common construction.

The backout post 10 comprises an upright pin having rotatably and vertically slidable thereon, a bracket 12. At the upper end of the pin is a transverse locking pin 13 held against removal by cotter pins or other similar devices. This locking pin limits the upward movement of the bracket 12. Between the bracket and the rotary table 3, I provide a spiral spring 14. This spring bears at its lower end upon the rotary table and at its upper end against the bracket with sufficient force to just support the bracket at its upper limit of movement. This allows the bracket to be easily depressed when it is necessary to adjust the same downwardly in use. The 100 bracket 12 is extended horizontally to form a support 15 which is slotted centrally at 16 to provide a space to receive the handle 17 of a pipe wrench 18. The slot 16 is open at its outer end, except for a stop pin 19 which 105 closes the said slot and also projects above

the bracket to provide a stop, the purpose of which will later appear.

At the inner end of the slot and centrally thereof is a pivot pin 20 upon which is mounted a cam-shaped lever 21. This lever is rigid with the pivot pin and rotates therewith. The upper end of the pin 20 projects above the bracket and has thereon a crank handle 22, by means of which the lever 10 may be swung toward or away from the wrench handle.

The wrench 18 shown in the drawing is secured firmly upon the pipe 8 by swinging the handle 17 in a clockwise direction, as 15 shown in that figure. Therefore, when the wrench is secured about the pipe the lever 21 in the slot will be swung away from the wrench handle so as to allow the said wrench handle to move to the right to obtain a grip 20 upon the pipe. The handle of the wrench is then swung in clockwise direction to lock the same firmly on the pipe and, in doing so, the lever 21 is swung into approximately the 25 position shown in Fig. 1. This will bring the handle 22 of the lever against a stop 23 which acts to limit the movement of the lever at the point where the outer end is farthest from the backout post. The handle of the wrench is then somewhat loosely locked between the lever and the stop pin 19. The 30 swinging of the rotary table in the clockwise direction will then swing the backout post and the wrench to the left, and will act to unscrew the joint of pipe. When the unscrewing action has been finished the handle 35 of the wrench is released by swinging the lever handle in a clockwise direction, as shown in the figure, thus swinging the cam away from the handle. This same swinging 40 movement of the handle 22 is continued forcibly until the said handle strikes against the stop pin 19. This gives the handle of the wrench a jar from the opposite side and serves to release it from the pipe after which 45 it may be unlatched and swung away from the pipe by a movement of the bracket upon the post 10. The handle of the wrench is provided with a series of openings 24 therein through which may be passed a pin 25 to 50 limit the longitudinal sliding of the handle in the bracket. This will serve, as will be obvious, to cause the movement of the wrench with the bracket when the bracket is swung away from the pipe.

55 While I have shown and described my preferred embodiment of the invention, it is obvious that various changes may be made therein without departing from the spirit of my invention. It is also obvious that while 60 I have shown the bracket as supporting a particular form of wrench, my invention is not confined to use with this particular tool, but may be used with any well known type of wrench now in use. The advantages of 65 the device lie particularly in the adjustabil-

ity of the bracket to accommodate the wrench to the joint in various positions of the joint and also in the manner in which the wrench may be firmly gripped to the pipe and quickly released. The swinging of 70 the cam lever away from the locking position is easily accomplished because of the particular cam shape in which the lever is constructed. Further advantage arises from the fact that the same swinging movement 75 which releases the handle also acts to jar the wrench upon the pipe by contact of the handle 22 with the pin 19 so that the wrench will automatically release itself without further action on the part of the operator. The 80 only thing remaining for the operator to do is to swing the jaws free of the pipe and to swing the wrench and the bracket out of their operative position. The further objects and advantages of this device will be 85 obvious to one skilled in the art.

What I claim as new and desire to protect by Letters Patent is:

1. In a device of the character described, a rotary table, a backout post secured therein 90 comprising an upright pin, a bracket slideable vertically thereon, a spring on said pin bearing against said table and said bracket, said bracket having a handle receiving slot therein, a cam shaped lever in said slot, and 95 means to swing said lever laterally in said slot.

2. In a device of the character described, a rotary table, a backout post secured therein 100 comprising an upright pin, a resiliently supported bracket slideable vertically thereon, said bracket having a handle receiving slot therein, a cam shaped lever in said slot and means to operate said lever.

3. In a device of the character described, a rotary table, a backout post secured therein 105 comprising an upright pin, a resiliently supported bracket slideable vertically thereon, said bracket having a handle receiving slot therein, a stop pin at the outer end of 110 said slot projecting above said bracket, a cam shaped lever in said slot, and a handle on said lever adapted to swing said lever and to contact with said stop pin.

4. In a device of the character described, a rotary table, a backout post secured therein 115 comprising an upright pin, a bracket slideable thereon, a lateral slot in said bracket, a wrench handle received in said slot, a cam shaped lever in said slot adjacent said pin, 120 and means to swing said lever in said slot to lock or release said handle, for the purpose described.

5. In a device of the character described, a rotary table, a backout post secured therein 125 comprising an upright pin, a bracket on said pin, a lateral slot in said bracket, a wrench handle received in said slot, a stop pin at the outer end of said slot, a lever in said slot adapted to bear against said handle 130

and means to operate said lever to lock or release said handle.

6. A backout post comprising an upright pin, a resiliently supported bracket thereon, a lateral support on said bracket, a stop at the outer end thereof, a lever on said support and means to swing said lever on said support toward or away from said stop pin.

7. A backout post comprising an upright pin, a spring thereon, a bracket supported on said spring and slidably and rotatable on said pin, a laterally projecting support on

said bracket, a wrench handle slideable on said support, and a locking means on said support.

8. A backout post comprising an upright pin, a bracket thereon, a lever on said bracket, a stop means at the outer end of said bracket and means to swing said lever toward and from said stop.

In testimony whereof, I hereunto affix my signature, this the 6th day of September, A. D. 1921.

WILLIAM L. CHILDS.
